NECKTIE STRETCHER

Filed Nov. 15, 1929

Inventor:
William H. Wilson,
By Wm. F. Freudenberg,
Atty.

UNITED STATES PATENT OFFICE

WILLIAM H. WILSON, OF CHICAGO, ILLINOIS

NECKTIE STRETCHER

Application filed November 15, 1929. Serial No. 407,420.

The present invention relates to devices adapted to be inserted in the ends of neckties or other articles and stretch the fabric until it is taut and free from wrinkles. The object of the present invention is to produce a device of this kind that shall be simple and compact, capable of being easily applied and removed, and effective in operation.

In carrying out my invention I employ a form which, after being inserted in the article to be stretched or held, may readily be adjusted to fit the contour of the article and hold it taut under any desired tension. This I accomplish by bending a member in the form of a stiff wire or a small rod or bar into a rudimentary shape and connecting the ends of such member together by means of a toggle device. When the toggle is straightened it spreads the form until it fills the article embracing it, the degree of tension to which the article is subjected being determined by the extent to which the toggle is straightened. By providing a suitable locking device for the toggle, the article may be maintained in its taut condition as long as desired. When the lock is released the form may be partially collapsed by means of the toggle, so that the form may be withdrawn from the work. In the case of a necktie holder and stretcher there may be two forms, one for each end of a tie, both forms being connected to the same toggle.

The various features of novelty whereby my invention is characterized will hereinafter be pointed out with particularity in the claim; but, for a full understanding of my invention and of its objects and advantages, reference may be had to the following detailed description taken in connection with the accompanying drawing, wherein:

Figure 1 is a rear elevation of a device embodying my invention, shown collapsed in full lines and expanded in dotted lines; Fig. 2 is an end view, on a larger scale; Fig. 3 is a view, on a still larger scale, partly in section, showing the manner of attaching the ends of the wires to the toggle; and Fig. 4 is a section on line 4-4 of Fig. 3.

In the drawing I have illustrated my device as adapted for use in connection with so-called four-in-hand neckties and the de-

tailed description will be confined to this particular embodiment; although it will of course be understood that the expandible form or forms may take any desired shape to adapt the device to other articles.

Referring to the drawing, 1 and 2 represent two forms of wire, small rods, bars or strips or other long bendable, and preferably resilient, members, to which I shall refer as wire-like members, bent into the shape of long narrow V's; the member 1 being longer and wider, at least at the base, than the member 2. The legs of each form are hinged to the two arms or levers of a toggle; the member 1 being conveniently connected to the two ends of the toggle and the member 2 to the arms of the toggle at points between the ends and the toggle joint. When the toggle is collapsed, the legs of the forms are drawn toward each other and, when the toggle is straightened the legs are spread apart.

In using the device, the forms are contracted or collapsed as shown in full lines in Fig. 1; the ends of a necktie are slipped over the forms; and the toggle is then straightened or partially straightened until the fabric of the tie is drawn taut. Since neckties differ in width, the toggle will not always be straight when the desired degree of tautness of the necktie fabric has been produced and, therefore, I provide means for locking the toggle with its arms or levers on any desired angular relation to each other.

The structural details of the toggle and the connections between the same and the forms may of course be widely varied. In the preferred arrangement shown, each arm or lever of the toggle is composed of two spaced parallel bars, as indicated at 3, 3 and 4, 4, the two bars of one pair overlapping the bars of the other pair at their meeting ends. A screw 5 passes through the overlapping ends of the bars and is provided with a wing nut 6. When the nut is loosened the toggle may be straightened or collapsed and, when the nut is tightened, the arms of the toggle are locked against relative movement.

For the purpose of fastening the forms to the toggle, each leg has at its end an eye 7, conveniently formed by bending the wire-like

member. These eyes lie in the spaces between the bars of the toggle and are engaged by pintles 8 passing through the same from one bar to the opposite bar. These pintles may be of any desired kind, conveniently tubular sheet metal rivets, as shown.

In order to make it easier to apply the necktie to the forms I prefer that the latter be located in planes spaced apart from each other. This may conveniently be accomplished by making a double bend in each of the legs of one of the forms, near the toggle, thereby offsetting this form from the other. In the arrangement shown, it is the smaller form 2 which is offset, each of its legs being bent laterally at right angles to the plane of the form at a point near the toggle, as indicated at 9, and then back parallel with said plane as indicated at 10.

It will thus be seen that I have produced an extremely simple device which automatically adjusts itself to articles of various sizes, so that no skill is required to apply it and secure and maintain the desired tension in any given article; which takes up but little room, so that one or more may be kept in a bureau or dresser drawer; and which may be used as a hanger to hold the necktie or other article suspended and permit it to dry quickly, if it has been dampened to facilitate the removal of wrinkles.

While I have illustrated and described with particularity only a single preferred form of my invention, I do not desire to be limited to the exact structural details thus illustrated and described; but intend to cover all forms and arrangements which come within the definitions of my invention constituting the appended claim.

40 I claim:—

A device of the character described comprising two V-shaped members, a toggle, a hinge connection between one leg of each V and one of the arms of the toggle, and a hinge connection between the other leg of each V and the remaining arm of the toggle, the hinge connections between each member and the toggle being equally spaced from the joint in the toggle, and the hinge connections between one of said members and the toggle being nearer the said joint than are the other hinge connections.

In testimony whereof, I sign this specification.

55 WILLIAM H. WILSON.
